J. S. CARL

SCRAPER FOR GOLF GREENS

Filed March 30, 1926

Patented Dec. 13, 1927.

1,652,852

UNITED STATES PATENT OFFICE.

JOHN S. CARL, OF DALLAS, TEXAS, ASSIGNOR TO THEODORE A. SALA, OF DALLAS, TEXAS.

SCRAPER FOR GOLF GREENS.

Application filed March 30, 1926. Serial No. 98,472.

This invention relates to new and useful improvements in scrapers for golf greens.

The invention has particularly to do with a scraper for use in smoothing the surface 5 of a sand green so that a clear and smooth path between the ball and the cup may be obtained.

A particular object of the invention is to provide a scraper arranged to fold into an 10 elongated compact shape so that it may be carried in the golf bag like a stick.

A further object of the invention is to provide a scraper which may be used entirely with one hand in withdrawing it from 15 the bag and unfolding it into operative position.

Another object of the invention is to provide a scraper with a spring actuated scraping bar, whereby it is automatically swung 20 into position when released; together with a positive stop and dog for holding the said bar rigidly while scraping.

A construction designed to carry out the invention will be hereinafter described together with other features of the invention. 25

The invention will be more readily understood from a reading of the following specification and by reference to the accompanying drawings, in which an example of the 30 invention is shown and wherein:

Fig. 1 is a plan view of a scraper constructed in accordance with my invention and in its folded position, the unfolded 35 scraper bar being indicated in dotted lines,

Fig. 2 is a similar view of the scraper unfolded and ready for use,

Fig. 3 is an enlarged detail of a portion of one side of the scraper,

Fig. 4 is a detail of a portion of the other 40 side, and

Fig. 5 is a perspective view of a sand green with the scraper in its operative position.

In the drawings the numeral 10 designates 45 an elongated handle suitably shaped and merged into a head 11 at one end. The head is recessed at 12 for the greater portion of its length to receive one section of a flat scraper bar 13, centrally on a rivet 14 passing 50 through the outer end of the head. The head has an oblique undercut shoulder 15 at the inner end of its recess 12 and one end 16 of the bar is cut to abut said shoulder to limit the inward swing of the bar, thereby

alinng the bar with the head. The bar fills 55 the recess flush with the head.

When the scraper is folded the bar extends beyond the head, but in line therewith, thus making the entire structure about the length of an ordinary golf club and about the same 60 size as the stick thereof. A latch 17 is pivoted intermediate its ends on the side of the head so as to overlie the adjacent end of the folded bar 13 and hold the latter in the recess. This latch has a shank 18 normally 65 held against a stop pin 20 by a leaf spring 19 fastened to the handle 10. By pressing down on the shank, the latch is swung (dotted lines Fig. 3) to release the bar. The swing of the latch is limited by a second 70 pin 21.

A light coiled spring 22 extending from an eye 23 in the edge of the bar 13 and outwardly of the rivet 14 has its inner end secured to an eye 24 at the side of the head. 75 As is shown in Fig. 1, this spring is tensioned when the bar 13 is folded and when the latch is pressed to release the bar, said spring swings it outwardly to the right angular position shown in dotted lines in Fig. 80 1. In order to hold the bar in this position, a stop plate 25 is fastened to the side of the head and has a lug 26 extending upwardly into the path of the bar, as is best shown in Fig. 4.

To assure rigidity and prevent folding of the bar, a dog 27 is pivoted to the opposite side of the head. This dog has its forward end notched at 28 to engage over the back edge of the bar 13. A leaf spring 30 engaging under the shank 29 of the dog holds the latter in engagement with said bar. It will be seen that the lug 26 on one side of the head and the dog on the other side, firmly hold the bar 13 in scraping position. 95 It is pointed out that when the bar is thus held its front scraping edge is free from obstructions.

When the scraper is carried in the golf bag the bar 13 is folded into the recess 12 and held by the latch 17. When the player desires to use the scraper, he grasps the same at the latch with one hand and withdraws it from the bag. By pressing down on the latch 17 (Fig. 3) the latter is swung out of 100 the path of the bar 13 and the spring 22 is then free to swing the said bar. When the bar is swung outward it contacts with the

stop lug 26, rides under the dog 27 and engages in the notch 28, thus being fastened in position.

The scraper will be in the position shown 5 in Fig. 1 and the player merely has to adjust the handle 10 in his hand so that he may conveniently incline it as is shown in Fig. 5 and draw the bar across the green, thus scraping and making a smooth path to the 10 cup. After he has used the scraper the same is folded and returned to the golf bag.

Various changes in the size and shape of the different parts, as well as modifications and alterations, may be made within the 15 scope of the appended claims.

What I claim, is:

1. In a sand green scraper, the combination of a handle, a scraper bar pivoted intermediate its ends to the handle and having 20 one end adapted to be folded into parallelism therewith, a latch on the handle for holding the bar folded in line with the handle, and a spring connected with the handle and the bar for swinging the bar transversely in a 25 plane parallel to the handle when the latch is released.

2. In a sand green scraper, the combination of a handle, a scraper bar pivoted intermediate its ends to the handle and having 30 one end adapted to be folded into parallelism therewith, a latch on the handle for holding the bar folded in line with the handle, a spring connected with the handle and the bar for swinging the bar transversely in a plane 35 parallel to the handle when the latch is released, and a stop for holding the bar transversely of the handle.

3. In a sand green scraper, the combination of a handle, a scraper bar pivoted to the 40 handle and adapted to be folded in line therewith, a latch on the handle for holding the bar folded in line with the handle a

spring connected with the handle and the bar and tensioned when the bar is folded to effect an automatic unfolding the bar when 45 the latch is released, a stop for holding the bar transversely of the handle, and means for automatically fastening the bar in its transverse position when engaging said stop.

4. In a sand green scraper, the combination of a handle, a head at the end of the handle, a scraper bar pivoted to the head for folding into parallel relation thereto, a spring connected with the head and bar for swinging the latter transversely of the head, 55 a latch on the handle for holding and releasing the bar, a stop for limiting the outward swing of the bar, and a dog for fastening the bar against the stop.

5. In a sand green scraper, the combination of a handle, a head at the end of the handle in line therewith, said head having a longitudinally extending recess, a scraper bar pivoted intermediate its ends to the head and mounted to fold at one end into the recess, a 65 coiled spring connected with the bar and head and tensioned when the bar is folded into said recess, and a latch on the handle for holding the bar in the recess.

6. In a sand green scraper, the combination of a handle, a head at the end of the handle in line therewith, said head having a recess, a scraper bar pivoted to the head and mounted to fold into the recess, a coiled 70 spring connected with the bar and head and tensioned when the bar is folded into said recess, a latch on the handle for holding the bar in the recess, a stop lug in the path of the bar one side of the head, and a dog on the opposite side of the head engaging the 75 bar.

In testimony whereof I affix my signature.

JOHN S. CARL.
